UNITED STATES PATENT OFFICE.

JACOB A. THOMAS AND WILLIAM W. DRISCOLL, OF READING,
PENNSYLVANIA.

DESIGN FOR A NOZZLE.

SPECIFICATION forming part of Design No. 28,692, dated May 24, 1898.

Application filed April 8, 1898. Serial No. 676,961. Term of patent 3½ years.

To all whom it may concern:

Be it known that we, JACOB A. THOMAS and WILLIAM W. DRISCOLL, citizens of the United States, residing at Reading, in the county of Berks and State of Pennsylvania, have invented and produced a new and original Design for Nozzles; and we do hereby declare the following to be a full, clear, and exact description of the same, reference being had to the accompanying drawings, forming a part thereof.

In the accompanying drawings, Figure 1 is a perspective view of a nozzle embodying our design, and Fig. 2 is a vertical longitudinal section through the same.

The leading feature of our design consists of a cylindrical hollow body portion flaring outwardly from a suitable point in its length and from said point flaring rearwardly to form a shoulder, another shoulder being formed at the extreme end of the nozzle in the rear of the first-mentioned shoulder, with a peripheral groove or recess between the two shoulders, the bore extending through the entire length of the nozzle.

A in the drawings represents a nozzle made in accordance with our design, which is formed with a cylindrical hollow body portion a , the bore extending the entire length of the nozzle. The body portion of the nozzle flares outwardly from a point, as at a' , in its length to its extreme end a^2 , thus forming a flaring cylindrical mouth or discharge end. From the point a' the body portion of the nozzle flares rearwardly to form a shoulder a^3 . Another shoulder a^4 is formed on the extreme rear end of the nozzle in rear of the shoulder a^3 , with a peripheral groove or recess a^5 between them.

Having now described our design, what we claim as new, and desire to secure by Letters Patent, is—

The design for a nozzle, substantially as herein shown and described.

In testimony whereof we hereunto affix our signatures in presence of two witnesses.

JACOB A. THOMAS.
WILLIAM W. DRISCOLL.
